PORTABLE COMMUNION SET CASE

Christian H. Rohlfing, St. Charles, Mo.

Application May 8, 1950, Serial No. 9,780

Term of patent 14 years

(Cl. D29—23)

To all whom it may concern:

Be it known that I, Christian H. Rohlfing, a citizen of the United States and a resident of St. Charles county, State of Missouri, have invented a new, original, and ornamental Design for a Portable Communion Set Case, of which the following is a specification, reference being had to the accompanying drawing, forming part hereof.

Fig. 1 is a front elevational view of a portable communion set case, showing my new design,

Fig. 2 is a top plan view of the communion set case,

Fig. 3 is an elevational view looking at an end of the communion set case, and

Fig. 4 is a perspective view thereof.

I claim:

The ornamental design for a portable communion set case, substantially as shown.

CHRISTIAN H. ROHLFING.
